(57) **CLAIM**

The ornamental design for a loudspeaker diaphragm, as shown and described.

DESCRIPTION

FIG. 1 is a front elevation view of a loudspeaker diaphragm showing our new design;

FIG. 2 is a left side elevation thereof, the right side elevation being a mirror image thereof;

FIG. 3 is a top plan view thereof;

FIG. 4 is a cross sectional view thereof, taken along line 4-4 of FIG. 3; and,

FIG. 5 is an enlarged cross sectional view of the wavy part of the loudspeaker diaphragm.

The broken lines indicate the unclaimed portions and form no part of the claimed design.
